UNITED STATES PATENT OFFICE

2,650,527

PHOTOGRAPHIC PRINT TREATING APPARATUS

Arthur W. Caps, Rochester, N. Y., assignor to
Photostat Corporation, a corporation of Rhode
Island

Application August 18, 1951, Serial No. 242,453

11 Claims. (Cl. 95—89)

1
This invention relates to improvements in a photographic print treating apparatus.

In photo copying documents and the like, the copy print after exposure is delivered in sheet form and picked up by a suitable conveyor to be carried through a developing bath, a rinsing bath, and thereafter deposited into a fixation or "hypo"-bath. It is desirable that the print be quickly submerged into the "hypo"-bath after passing through the developer. If the print is not submerged at once after leaving the developer, exposure to the air causes spots to form and the print is spoiled. It is further desirable to deposit prints face up in the "hypo"-bath in order that the same may be viewed for checking of the same prior to complete fixation thereof.

One of the objects of the invention is to provide a fixation apparatus which will cause the print after being deposited into the bath to be quickly submerged therein.

Another object of the invention is to provide an apparatus for the fixation bath so constructed and operable as to cause a suction action on the print deposited therein to quickly submerge the same.

Another object of the invention is a circulation of the bath liquid from the bottom to the top of the bath container.

Another object of the invention is to provide an apparatus for the fixation bath so constructed as to cause the prints to be deposited face up therein and quickly submerged.

Another object of the invention is to provide an apparatus for the fixation bath so constructed as to provide for a pumping action of the bath liquid to circulate the same from top to bottom.

A more specific object of the invention is to provide an apparatus for a print treating bath so constructed that by relative movement of parts of the container for the treating bath a pumping action will be had for circulating the bath liquid.

With these and other objects in view, the invention consists of certain novel features of construction, as will be more fully described and particularly pointed out in the appended claims.

In the accompanying drawings:

Fig. 1 is a sectional view taken laterally through the apparatus embodying my invention;

Fig. 2 is a similar view showing the apparatus in a different position;

Fig. 3 is a sectional view taken substantially along line 3—3 of Fig. 1; and

Fig. 4 is a plan view thereof.

In carrying out my invention, I provide two containers or tanks for the treating liquid and

2
mount these one within the other in spaced relation and arranged so as to provide for a relative reciprocal movement therebetween, which movement may be conveniently provided by mounting one of the tanks so as to be oscillated in a single plane. The inner tank is preferably held stationary and receives the print to be treated. The inner tank is made of a much smaller size in the direction of the movement of the outer container so as to provide a space between the container in this dimension thereof a distance slightly greater than the distance of movement of the said outer container. At one limit of movement of the outer container, the adjacent sides of said containers at one side thereof in the direction of movement will be at a minimum spacing while at the opposite side of the container the adjacent sides thereof will be at a maximum distance; thus, as the container is reciprocated the said spacing between the containers on opposite sides thereof will alternately increase and decrease from the minimum to the maximum distance, respectively. The other adjacent sides of the tanks are relatively closely spaced to each other and this spacing remains substantially constant. The inner tank is provided with oppositely disposed passages through which liquid flows from the inner container into the outer container to fill the spacing therebetween. These passages are controlled by simple valve mechanism normally moved by gravity to closed position and also moved to the open and closed position by the pressure of the moving bath liquid thereon, depending upon the relative direction of movement of the said liquid, the arrangement being such that the valve will be closed to a return flow from the outer container and opened for an outward flow of liquid from the inner container. In one direction of movement of the outer container, the liquid in the spacing between the containers will be displaced and moved upwardly along the adjacent walls of the containers to overflow into the inner container, while on the opposite side of the containers, the spacing between the adjacent walls will increase and by the flow of liquid from the inner container through the open valve of the adjacent passage. Thus, the relative movement of the containers provides a pumping action whereby the liquid is taken outwardly from the bottom of the inner tank and then poured back therein over the top thereof. This action sets up a downward movement of the liquid within the inner container and causes a suction on a print deposited on the surface of the bath, which quickly submerges the print for fixation to start

immediately over the entire print. Thus I am able to deposit prints for fixation face up in the bath without danger of exposure to air sufficient to develop spots therein.

Referring to the drawings for a more detailed description of the invention, 10 designates generally an apparatus for treating photographic prints, more particularly a fixation bath, for a print. The apparatus 10 in the present instance is constructed to make it particularly adapted to be employed in connection with known cameras employed for copying documents and the like, and only so much of which is shown for a clear understanding of the invention. It may be here noted that after exposure the print is delivered in sheet form to be picked up by a chain conveyor having opposite stretches 11 which carry a pin bar 12 (Fig. 1) armed with spaced pins 13 on which one marginal edge of the print is impaled to be carried by the conveyor to be passed through a developing bath, a rinsing bath, and then carried to be deposited into the "hypo"-bath for the fixation thereof.

The apparatus 10 includes an inner open tank 14, preferably fabricated of sheet metal and made of rectangular form providing opposite side walls 15, 15', end walls 16, and a bottom wall designated generally 17 (Fig. 2). This bottom wall 17 is depressed centrally and in a longitudinal direction and provides a well 18 having opposite walls 19, 19' which extend substantially at right angles to the bottom wall portions 20, 20'. The walls 19, 19' each have a similar opening 21, 21', respectively, which extend substantially the entire length of the said walls 19, 19'. The upper marginal edge portions 22 of the walls 15, 15' are bent to extend inwardly and downwardly inclined to the horizontal. The walls 16 are extended above the effective height of the walls 15, 15' and each has a crossbar 23 attached to the upper marginal edge thereof as by means of screws 24. Each bar 23 is similar to the other and is of a length to extend substantially equal distances beyond the sides of the tank 14 and these extending end portions are each provided with a threaded opening 25.

L-shaped brackets 26 providing foot portions 27 are secured on the side walls 28 of the body of the casing as by means of screws 29. There are four of these brackets, two of which are positioned on one wall 28 and the other two on the opposite wall 28 with the brackets on one of said walls being in line with the brackets on the other wall and with the foot portions 27 thereof extending inwardly toward each other. The bars 23 are attached to these foot portions 27 by means of screws 30 which will suspend and hold the tank 14 in a stationary position.

There is also provided an outer tank 31 (Fig. 1) also made rectangular in form and of sheet metal providing a bottom wall 32, side walls 33, 33', and end walls 34 (Fig. 3) respectively. The upper marginal edge of these side and end walls 33, 33' and 34 are also bent inwardly and downward as at 34' on an incline to the horizontal. There is attached to the outer side of the bottom wall 32 at each corner thereof an angle bracket 35, the foot portion 36 (see Fig. 3) of which provides a mounting ear having a threaded opening therethrough. The tank 31 is positioned to enclose the sides and bottom of the tank 14 in spaced relation therewith and is mounted for reciprocal movement laterally of the body of the camera casing as by means of links 37 which are pivotally attached at the upper end thereof to the

bars 23 as at 33 and pivotally secured at their lower ends to the said ears 36 by means of studs 39. The edges of the tank 31 extend a substantial distance above the walls 15, 15' of the inner tank 14 and in the direction of relative movement between the tanks to provide a spacing between the walls 15, 33 and 15', 33', a combined distance slightly greater than the distance of movement of the said tank in one direction, the spacing between the walls 14 and 34' is only that necessary for clearance. The tank 31 is oscillated or reciprocally moved by means of an eccentric 41 which is fixed to a vertically disposed shaft 42 (see Fig. 1) journalled in a bearing 43 secured to the body of the camera casing. Motion is transmitted from a power shaft 44 (Fig. 4) by means of a pair of engaging miter gears 45, one of which is attached to the shaft 44 and the other to the shaft 42. The eccentric 41 is in turn connected to the tank 31 by means of a link 46 pivotally attached to the crank 41 by means of a pivot stud 47 and extends therefrom to be pivotally attached to the bottom of the tank 31 by means of a pivot stud 48 threadingly engaging a boss 49 fixed to the bottom of the tank 23.

The openings 21, 21' are controlled in the instant disclosure by means of simple, flapper valves 50, 50' (Fig. 2) which are loosely pivoted as at 51, 52 to be moved by gravity to closed position. The lower edges of these valves engage against the lower marginal edges about said openings to provide an abutment to engage in the closed position. These valves are also movable by the pressure of the fluid when in motion to open or close the same, depending upon the direction of motion of said liquid. The arrangement is such as to provide for the valves to be open to the out flow of liquid from said inner container and to be closed to a return flow of liquid from the outer container.

The operation of the apparatus will be apparent from the above description, the tank 14 being filled with a print treating liquid to the proper level which through the openings 21, 21' will flow into the outer tank 31 to find its level therein. Upon the oscillation of the outer tank (see Fig. 1), the space between the walls 33 and 15 will be decreased by the movement of these two walls toward each other, these walls being substantially parallel to each other and moved in a direction at right angles to the surface of the liquid within the containers. The decreasing distance between these walls 15 and 33 will be at a minimum distance, as shown in Fig. 2, at the outward limit of the throw of the crank 41. The liquid contained in the spacing between these two walls will be displaced to be moved upwardly along the walls and pour over the inclined top wall 22 into the tank 14 to flow over such prints which may be deposited in said inner tank 14. The space between the walls 15' and 33' will be increasing as the above movement occurs, causing a flow of liquid to be had from the inner container through the passage 19' into the outer container to fill this increasing space, which will also cause a downward movement of the liquid in container 14 to provide a suction action on the print to quickly submerge the same. On the reverse movement of the outer container 31, the walls 15', 33' will be moved toward each other and displace the liquid between these walls to cause the same to rise and flow over the adjacent inclined top wall 22, the increasing space between the opposite walls 15, 23 now being filled through the

opening 21 to complete a cycle of the above-described operation.

In order to prevent the print from being drawn into the well 18, a plurality of wires 53 are secured in position on the wall portion 20 to extend across the top of the well 18 and a perforated plate 54 is laid upon these wires 53.

I claim:

1. An apparatus for treating a photographic print comprising an outer container and an inner container within the same for a liquid for treating a print deposited into said inner container, said outer container having side walls spaced from side walls of said inner container and with the upper edge thereof extending above the upper edge of said inner container walls, means providing a passage for the flow of liquid from the inner container into the outer container to fill the space between said containers, means for mounting said containers for relative movement therebetween, said movement being in a direction at an angle to the surface of the liquid, and means for relatively moving said containers to displace the said liquid in the space between said containers to overflow from between said containers into the inner container.

2. An apparatus for treating a photographic print comprising an outer container and an inner container within the same for a liquid for treating a print deposited into said inner container, said outer container having side walls spaced from side walls of said inner container with the upper edge thereof extending above the upper edge of said inner container, a passage in the lower portion of said inner container for the flow of liquid therethrough from said inner container into the outer container to fill the space between said containers, means for mounting said containers for relative movement therebetween, said movement being in a direction at an angle to the surface of the liquid, means for relatively moving said containers to displace the said liquid in the space between said containers to overflow from between said containers into the inner container, and means for blocking said passage to the flow of liquid therethrough from said outer container.

3. An apparatus for treating a photographic print comprising an outer container and an inner container within the same for a liquid for treating a print deposited into the inner container, said outer container having side walls spaced from side walls of said inner container with the upper edge thereof extending above the upper edge of said inner container, means for supporting said inner container within said outer container, a passage from said inner container for the flow of liquid therethrough from the inner container into the said outer container to fill the space between said containers on one side thereof, a second passage from said inner container for the flow of liquid from the inner container into the said outer container to fill the space between said containers on the side thereof opposite to the said one side, means for mounting said containers for relative reciprocal movement therebetween for movement having a direction at an angle to the surface of the liquid, means for relatively moving said containers for reciprocal movement therebetween to decrease the space between said containers on one side thereof to displace the liquid therein to overflow from between said containers into the inner container and to increase the space between the containers on the said opposite side thereof to receive additional liquid from said inner container, and

means for blocking said passages to a return flow of liquid therethrough from said outer container into said inner container.

4. An apparatus for treating a photographic print comprising an outer container and an inner container within the same for a liquid for treating a print deposited into the inner container, said outer container having side walls spaced from side walls of said inner container with the upper edge thereof extending above the upper edge of said inner container, means for supporting said inner container within said outer container, a passage from said inner container for the flow of liquid therethrough from the inner container into the said outer container to fill the space between said containers on one side thereof, a second passage from said inner container for the flow of liquid from the inner container into the said outer container to fill the space between said containers on the side thereof opposite to the said one side, means for mounting said containers for relative reciprocal movement therebetween for movement having a direction at an angle to the surface of the liquid, means for relatively moving said containers for reciprocal movement therebetween to decrease the space between said containers on one side thereof to displace the liquid therein to overflow from between said containers into the inner container.

5. An apparatus for treating a photographic print comprising an outer container and an inner container within the same for a liquid for treating a print deposited into said inner container, said outer container having side walls spaced from side walls of said inner container and with the upper edge thereof extending above the upper edge of said inner container, means for supporting said inner container within said outer container, a passage in said inner container for the flow of liquid therethrough into said outer container to fill the space between said containers, means for blocking said passage to a return flow of liquid from the outer container into said inner container, means for mounting said containers for relative reciprocal movement therebetween, said movement being in a direction at an angle to the surface of the liquid, means for relatively oscillating said containers to displace the liquid contained in the space between said containers to overflow therefrom into the inner container over the top edge thereof.

6. An apparatus for treating a photographic print comprising an outer container and an inner container within the same for a liquid for treating a print deposited into the inner container, said outer container having side walls spaced from side walls of said inner container with the upper edge thereof extending above the upper edge of said inner container walls, means for mounting said outer container for reciprocal movement, said movement being in a direction at an angle to the surface of the liquid, means for suspending said inner container stationary and in spaced relation within said outer container, a passage in said inner container for the flow of liquid therethrough from said inner container into said outer container to fill the space between said containers, means for reciprocally moving said outer container to displace the liquid

contained in the space between said containers to overflow therefrom into the inner container and means for blocking said passage to a return flow of liquid from said outer container into said inner container.

7. An apparatus for treating a photographic print comprising an outer container and an inner container within the same for a liquid for treating a print deposited into said inner container, said outer container having side walls spaced from side walls of said inner container, means for mounting one of said containers for reciprocal movement relative to the other, means for reciprocally moving said containers relative to each other and means operable upon the relative movement of said containers to cause a downward movement of the liquid in the inner container to cause a suction action on said print to submerge the same.

8. An apparatus for treating a photographic print comprising an outer container and an inner container within the same for a liquid for treating a print deposited into said inner container, said outer container having side walls spaced from side walls of said inner container, means for suspending said inner container stationary within said outer container in spaced relation therewith, means for mounting said outer container for movement, said movement being in a direction at an angle to the surface of the liquid, a passage in said inner container for the flow of liquid therethrough from said inner container into said outer container to fill the space between said containers, a valve means operable for blocking a return flow of liquid through said passage from said outer container, and means for moving said outer containers to increase the spacing between said containers at one side thereof to cause a flow of liquid through said passage from said inner container into said outer container to fill the said increasing space and cause a downward movement of the liquid within said inner container to provide a suction on said print to quickly submerge the same.

9. An apparatus for treating a print in a fixation bath comprising an outer tank, an inner tank within the same for a fixation bath for treating a print deposited into the inner tank, said inner tank having a well opening into the bottom wall thereof, said outer tank having side walls spaced from side walls of the inner tank and with the upper edge thereof extending above the upper edge of the side walls of said well portion, a passage in said inner tank for the flow of liquid therethrough from said inner tank into the outer tank to fill the space between said tanks, means operable to block a return flow of liquid from said outer tank through said passage into said inner tank, means for conveying a print to be deposited into said inner tank, means for mounting said tanks for relative movement, said movement being in a direction at an angle to the surface of the liquid, and means for moving said tanks relative to each other to displace the liquid in the space between said tanks to overflow therefrom into said inner tank over said print and a perforated

plate in the bottom of the inner tank extending over the said well portion to block the passage of prints into said well portion.

10. An apparatus for treating a print to a fixation bath comprising an outer tank, an inner tank within the same, for a fixation bath for treating a print deposited into the inner tank, said outer tank having side walls spaced from side walls of the inner tank and with the upper edge thereof extending above the upper edge of said inner tank, a support extending laterally across body, means for mounting said outer tank on said support for reciprocal movement thereof laterally of said body, means for securing said inner tank on said support to be suspended therefrom, said inner tank having a passage therein for the flow of liquid therethrough from the inner tank into the outer tank to fill the space between said tanks, conveyor means for carrying a print to be deposited into said inner tank, means for blocking said passage to a return flow of liquid from said outer tank, and means for reciprocally moving said outer tank to displace the liquid in the space between said tanks to overflow therefrom into said inner tank and over said print.

11. An apparatus for treating a print to a fixation bath comprising an outer tank, an inner tank within the same, for a fixation bath for treating a print deposited into said inner tank, said outer tank having side walls spaced from side walls of the inner tank and with the upper edge thereof extending above the upper edge of said inner tank, a pair of supports extending laterally across body, a linkage for movably mounting said outer tank on said support for reciprocal movement laterally of said body, means for securing said inner tank to said supports to depend therefrom, said inner tank being spaced a greater distance from said outer tank lengthwise of said body than laterally thereof, a plurality of passages in the lower portion of said inner tank at a position opposite each other for the flow of liquid therethrough from the inner tank into the outer tank, valve means for controlling said passages normally moved by gravity to the closed position and moved to open position by the pressure of an out flow of fluid through said passages and moved to closed position by the pressure of a return flow of liquid through said passage from the outer container, and means for reciprocally moving said outer tank to decrease the space between said tanks at one side thereof to displace the liquid in said space to overflow into said inner tank and to increase the spacing between said tanks on the opposite side to cause the valve controlling the passage to said opposite side to open to the flow of liquid therethrough from the inner tank to fill said increasing space.
